PASTE TUBE

Wencil C. Dvorak, Dodge, Nebr.

Application March 7, 1938, Serial No. 194,458

4 Claims. (Cl. 221—60)

This invention relates to flexible paste tubes of the type usually employed for toothpaste, shaving cream, salves, and the like, and an object of the invention is to provide a paste tube having improved closure means therefor.

In accordance with the present invention the paste tube is provided with a valve for closing the neck thereof and means operable in response to pressure applied at a predetermined point on 10 the tube for moving the valve to an unseated position to permit the contents of the tube to exude therefrom.

The invention together with its objects and advantages will be best understood from a study 15 of the following description taken in connection with the accompanying drawings wherein—

Figure 1 is a plan view of the tube embodying the features of the present invention,

Figure 2 is a side elevational view thereof, 20 Figure 3 is an enlarged detail sectional view taken substantially on the line 3—3 of Figure 2,

Figure 4 is a view somewhat similar to Figure 3, but showing the valve in closed position, the valve being shown in open position in Figure 3,

Figure 5 is an enlarged fragmentary detail sectional view illustrating certain details hereinafter more fully referred to,

Figure 6 is a perspective view of the valve core and stem, and

Figure 7 is a detail sectional view taken substantially on the line 7—7 of Figure 2.

Referring to the drawings by reference numerals it will be seen that the improved flexible paste tube comprises the flexible tubular body 35 5 sealed at one end in the usual manner as at 6 and provided at the opposite end thereof with a shoulder portion 7 that is substantially rectangular in cross section as shown in Figure 7 and tapers to an integral neck 8.

The neck 8 is provided at the discharge end thereof with an internal conical valve seat 9 against which is adapted to normally seat the substantially conical valve core 10 provided on one end of a stem 11.

Anchored within the shoulder 7 adjacent the inner end of the shoulder is one end of a flat spring 12 to which is welded or otherwise secured as at 13 the inner end of the stem 11.

At the side thereof opposite to the anchored 50 end 14 of the spring 12 the shoulder 7 is formed to provide a recess 15 which accommodates the angular free end 16 of the aforementioned spring 12.

The portion of the tube 5 forming the outer 55 wall of the recess 15 is provided at point 17 in a

manner forming a finger seat whereby at the recess 15 the wall of the tube may be pressed inwardly for the purpose of bringing pressure against the end 16 of the spring to flex the spring inwardly to a position suggested in Figure 3 5 whereby to move the valve member 10 inwardly off of its seat 9 and thereby permit the contents of the tube, in response to external pressure on the tube, to exude therefrom.

At the inner end thereof the shoulder 7 is 10 provided with a cross brace 18 that at the end thereof forming the inner end wall of the recess 15 terminates short from the periphery of the tube 5 so as to permit the tube to shift longitudinally slightly relative to the shoulder 7 as is 15 necessary incidental to the compressing of the tube at the point 17 thereon.

Also so as not to interfere with the flexing inwardly of the spring 12 brace 18 is provided with an elongated slot 19.

It will thus be seen that normally under action of spring 12 valve member 10 seats within the seat 9 providing an efficient closure for the tube serving to exclude dirt from the tube.

When it is desired to discharge some of the 25 contents of the tube therefrom pressure with the thumb, preferably, engaging the wall in the region of recess 15 is applied at the point 17 to the wall of the tube and this pressure is transmitted to the end 16 of the spring 12 causing the latter to flex inwardly to the position shown in Figure 3. This obviously results in the valve 10 being drawn inwardly out of engagement with its seat 9 so that as external pressure is applied to the tube either by rolling the tube upon itself 30 as is sometimes done, or otherwise, some of the contents of the tube will be forced to exude therefrom through the neck 8.

Upon release of pressure at the point 17 spring 12 will spring back to its normal position urging 40 the valve member 10 into engagement with its seat 9 for substantially sealing the tube, the parts when the tube is sealed being as shown in Figure 4.

It is thought that a clear understanding of the 45 construction, utility and advantages of a flexible paste tube embodying the features of the present invention will be had without a more detailed description thereof.

Having thus described the invention what is 50 claimed as new is:

1. In a flexible paste tube, an integral neck provided internally thereof with a valve seat, a spring member anchored at one end within said tube and extending transversely of the tube, a 55

- valve stem secured at one end thereof to the spring intermediate the ends of the spring, a valve disk on the free end of said stem and normally urged by said spring into seating engagement with said valve seat, said spring adapted to bow longitudinally incidental to pressure being applied to the wall of the tube in a manner to flex a portion of said wall inwardly into engagement with the free end of the spring, to thereby draw said valve disk inwardly of the tube out of engagement with said valve seat.
2. In a flexible paste tube, an integral neck provided internally thereof with a valve seat, a spring member anchored at one end within said tube and extending transversely of the tube, a valve stem secured at one end thereof to the spring intermediate the ends of the spring, a valve disk on the free end of said stem and normally urged by said spring into seating engagement with said valve seat, said spring adapted to bow longitudinally incidental to pressure being applied to the wall of the tube in a manner to flex a portion of said wall inwardly into engagement with the free end of the spring, to thereby draw said valve disk inwardly of the tube out of engagement with said valve seat, and a brace extending transversely of said tube interiorly thereof, said brace at one end thereof and the wall of said tube being mutually separated so as not to interfere with the inward flexing of the tube wall when the latter is so flexed inwardly for flexing said spring, said spring being dis-

posed intermediate said brace and the neck-equipped end of the tube.

3. In a flexible paste tube of the character described, an integral neck, a transverse spring member mounted internally of the tube and adapted to be flexed longitudinally incidental to the application of pressure laterally to the tube at a point substantially in alignment with said spring member, a valve stem secured at one end thereof to said spring intermediate the ends of the latter, and a closure member for said neck on the free end of said stems, and movable inwardly of the neck to an open position incidental to the aforementioned longitudinal flexing of said transverse spring member.

4. In a flexible paste tube of the character described, an integral neck, a transverse spring member mounted internally of the tube and adapted to be flexed longitudinally incidental to the application of pressure to the tube, a valve stem secured at one end thereof to said spring intermediate the ends of the latter, and a closure member for said neck on the free end of said stem, said tube at one side thereof being provided with an internal pocket, and said spring having the free end thereof extending into said pocket and provided with a lateral longitudinally curved projection to facilitate contact of the wall of the tube with the spring for flexing the latter incidental to pressure being applied to the wall of the tube in the region of said pocket.
